Patented Feb. 13, 1923.

UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

SPOTLIGHT.

Application filed November 16, 1921. Serial No. 515,440.

To all whom it may concern:

Be it known that I, ARTHUR L. STAPLES, a citizen of the United States, residing at New Haven, in the county of New Haven, 5 State of Connecticut, have invented certain new and useful Improvements in Spotlights; and I do hereby declare the following to be a full, clear, and exact description of the invention, such as will enable others skilled in 10 the art to which it appertains to make and use the same.

The present invention relates to battery hand lamps of the type in which the spread of the beam of light can be altered by varying the relative positions of the lamp and reflector.

It is an object of the present invention to provide a hand lamp in which the reflector has a substantially fixed position with respect to the casing and in which the desired change in the character of the beam of light delivered by the hand lamp is effected by shifting the lamp bulb with respect to the reflector. Hand lamps of this general character are disclosed and claimed in my co-pending application Serial No. 509,885, filed October 24, 1921.

It is a further object of the invention to protect the inner and fragile terminal of the lamp from the forward thrust and from destructive impact of the upper battery terminal, to provide for ready renewal of the lamp, to provide for easy access to various parts of the hand lamp mechanism, to insure 35 against shortcircuiting of the battery and inadvertent lighting of the lamp, and to secure other objects and advantages as hereinafter made clear.

In the accompanying drawing:—

40 Figure 1 is a sectional elevation of one embodiment of the invention;

Fig. 2 is a fragmentary section of the same embodiment;

45 Fig. 3 is a section through the front end of the hand lamp at right angles to the plane of Fig. 1;

Figs. 4, 5 and 6 are sections on the lines 4—4, 5—5 and 6—6 of Fig. 1, respectively;

50 Figs. 7 and 8 are details of the lamp adjusting mechanism;

Fig. 9 shows a modification in which the adjusting threaded shaft has a slot so that it can be turned with a screw-driver or a coin.

55 In the embodiment illustrated, the hand

lamp comprises a casing 1 of insulating material, such as fiber, in which are a plurality of dry cells 2 placed end to end in a pasteboard carton in conformity with usual practice. The naked bottom of the lowermost dry cell rests on and makes electrical connection with a coiled spring 3 carried by a metal closure or bottom cap 4 threaded to a collar 5 on casing 1. A metal strip 6 connects collar 5 with a switch housing 7 in conformity with usual practice. At the opposite or front end of casing 1 is a flaring metal head 8 fastened to the fiber casing by rivets 9 and having its front portion threaded to receive a lens-supporting ring 10 in the flanged edge of which the lens 11 is permanently mounted. A reflector 12 substantially parabolic in cross section has its outer flange gripped between collar 10 and the front edge of head 8 so that the reflector is clamped in fixed relation to the casing.

Coiled spring 3 holds the battery of dry cells with yielding pressure against the abutment at the front end of the battery. This abutment comprises a metal shell or bridge 13 (Fig. 6) the outer ends or edges 14 of which are turned up as shown in Fig. 3, and are secured to the wall of fiber casing 1, as by rivets 15. A washer 16 of insulating material is preferably introduced between the battery and the metal bridge to insulate the upper zinc edge of the battery. At the center of this bridge or abutment and preferably integral therewith is a cylinder 17 which serves as a guide for a movable lamp support. The lamp support comprises a plunger 18 of insulating material cylindrical in form and movable up and down in cylinder 17. The hollow upper end of this lamp support is threaded to serve as a socket for an incandescent lamp 19. The lamp can advantageously be of the type wherein the light-giving filament is concentrated within a small area. Plunger 18 has a diagonal hole for the reception of a nut 20, the outer surface of which is inclined as shown in Fig. 7. This nut has threaded engagement with a transverse shaft 21, one end of which protrudes through the side of the casing and is provided with a knurled button 22 by which the shaft may be rotated to cause forward or backward movement of the nut along the shaft with resultant forward or backward movement of the 110

lamp support axially of the casing and of the reflector secured thereto. A metal collar 23 is slipped over the upper reduced end of plunger 18 and has an integral finger 24 (Figs. 1 and 4) struck up therefrom which passes through a slot 25 (Fig. 4) and makes electrical connection with the threaded terminal of the lamp. Integral with this collar is a lug 26, the outer end of which makes electrical connection with the front yielding end of a stationary contact strip 27. Strip 27 is held in place by a rivet 28 and its lower end is bent to form a finger 29 which protrudes through a slot in the fiber casing and forms one of the contacts of the switch mechanism by which the flow of battery current to the lamp bulb is controlled. The other switch element is a flexible leaf spring 30 fastened to housing 7 by a rivet 31 and having a thumb pan or push button 32 by which it can be manipulated. Other forms of switch mechanism can be used in place of that shown in the drawing.

Electrical connection between the upper terminal 33 of the battery and the inner terminal 34 of the lamp is attained by means of a bronze spring 35, the lower end of which passes through a slot 37 in the insulating plunger to engage with battery terminal 33. The spring is under compression so that the lower end remains in contact with the battery terminal irrespective of adjustments in the position of the lamp and resultant movement of the upper end of the spring 35.

With the arrangement above described, the battery circuit is from battery terminal 33 through spring 35 to the inner terminal of the lamp, then through the lamp to finger 24 and then through collar 23, lug 26, strip 27, finger 29, spring 30, housing 7, conductor 6, collar 5, cap 4 and spring 3 to the other terminal of the battery.

The opening in reflector 12 is large enough to permit free sliding movement therethrough of plunger 18 so that by turning button 22 and its attached shaft 21, the nut 20 will be caused to move along the shaft transversely of the casing and will cause the insulating lamp support to travel axially of the hand lamp, thereby shifting the lamp with respect to the reflector and thus changing the character of the beam of light delivered by the hand lamp by changing the focus of the rays of light from the lamp bulb. With a hand lamp as thus constructed, the rays of light may be focused on a distant object or may be spread over a relatively wide area, as desired. Through-out the manipulation, the battery remains stationary in the casing and is firmly held against its abutment by coiled spring 3. Electrical connection from the upper battery terminal 33 is at all times maintained by spring 35. Similarly, lug 26, by sliding

along the yielding and inwardly pressing end of spring strip 27, will maintain electrical connection to the other terminal of the lamp. Upward and downward movement of the lamp support is limited by the engagement of nut 20 with metal cylinder 17.

In the modification illustrated in Fig. 9, the transverse threaded shaft 21', on which nut 20' is mounted, does not have a knurled wheel or button like that at 22 in Fig. 3, but terminates substantially flush with the outer wall of the casing in a flat head 36 in which is a slot or groove adapted to receive a screw driver or the edge of a coin, such as a dime or penny. Through the use of a screw driver or a coin this shaft can be rotated much as if provided with a wheel or button. This construction has the advantage of leaving the front end of the casing unencumbered with projecting parts. Also there is less likelihood of inadvertent shifting of the lamp through careless handling of the device.

In the embodiment shown in the drawings, the casing is of insulating material, but the present invention is applicable to metal casings by merely insulating conductor 27 from the casing, as by the insertion of a strip of insulating material between the two and the use of insulated rivets. In the embodiment illustrated, the battery is well protected against short circuit and inadvertent lighting of the lamp will not occur when the lamp is laid on a metal surface or placed among metal tools. The inner lamp terminal is protected from destructive pressure and the hand lamp as a whole has many advantages that will be apparent to those skilled in the art.

Changes in structural details and in the arrangement of the several parts may be made without departing from the spirit of my invention as defined by the appended claims.

I claim:

1. In a hand lamp, the combination of a casing, a battery and a lamp therein co-axially with one another, a reflector for said lamp, and means rotatable on an axis transverse of said casing for moving said lamp with respect to said battery and said reflector to change the spread of the beam of light delivered by said hand lamp.

2. In a hand lamp, the combination of a casing, a battery and a lamp therein co-axially with one another, a reflector for said lamp, a rotatable member operable from the outside of said casing and a nut threaded to said rotatable member and having an inclined face to slide said lamp axially of said casing and reflector and thereby change the spread of the beam of light delivered by said hand lamp.

3. In a hand lamp, the combination of a casing, a battery and a lamp therein co-axial-

- ally with one another, a reflector for said lamp, a shaft extending across said casing transversely to the axis thereof, and means actuated by said shaft for moving said lamp 5 with respect to said reflector to change the spread of the beam of light delivered by said hand lamp.
4. In a hand lamp, the combination of a casing, a battery and a lamp therein co-axially with one another, a reflector for said lamp, a shaft extending into said casing at right angles to the axis thereof, and means threaded to travel along said shaft and operatively connected to slide said lamp axially 10 of said casing and reflector and thereby change the spread of the beam of light delivered by said hand lamp.
5. In a hand lamp, the combination of a casing, a battery and a lamp therein, a reflector for said lamp, a threaded shaft positioned transversely of said casing, and means actuated by the rotation of said shaft to slide said lamp with respect to said battery and reflector to change the spread of the beam 15 of light delivered by said hand lamp.
6. In a hand lamp, the combination of a casing, a battery and a lamp therein, a reflector for said lamp, a threaded shaft positioned transversely of said casing, a nut 20 thereon, and means actuated by said nut to move said lamp axially of said casing when said shaft is rotated.
7. In a hand lamp, the combination of a casing, a battery and a lamp therein, a fixed abutment for the front end of said battery, a reflector for said lamp, and a rotatable shaft 25 operatively connected to move said lamp with respect to said abutment when the spread of the beam of light delivered by said hand lamp is to be altered.
8. In a hand lamp, the combination of a casing, a battery and a lamp therein, a fixed abutment for the front end of said battery, a reflector for said lamp, a rotatable shaft 30 positioned transversely of said casing, and means threaded to said shaft for moving said lamp with respect to said abutment to change the spread of the beam of light delivered by said hand lamp.
9. In a hand lamp, the combination of a casing, a battery and a reflector therein, a fixed abutment for said battery, a lamp support 35 mounted to slide in said abutment, a lamp carried by said support, and means rotatable within said casing for sliding said support in said abutment to move said lamp with respect to said reflector.
10. In a hand lamp, the combination of a casing, a battery and a reflector therein, a fixed abutment for said battery, said abutment having a tubular extension, a lamp carried by said support, a shaft mounted transversely of said casing, and means actuated by said shaft and engaging said lamp support 40 to move said lamp support in said abutment and thereby change the spread of the beam of light delivered by said hand lamp.
11. In a hand lamp, the combination of a casing, a battery and a reflector therein, an abutment for said battery, a lamp support 45 mounted to slide in said abutment, a lamp carried by said support, an adjusting shaft positioned transversely of said casing, and a nut threaded thereto and having an inclined face engaging said lamp support to move the same axially of the hand lamp when said shaft is rotated.
12. In a hand lamp, the combination of a casing, a battery therein, a battery abutment secured to said casing, a spring holding said battery against said abutment, a metal head at the front end of said casing, a lens and a reflector secured to the front end of said head, a lamp support mounted to slide in said abutment, a lamp carried by said support, an adjusting shaft, and a nut threaded to said shaft and operative to move said support to change the character of the beam of light delivered by said hand lamp.
13. In a hand lamp, the combination of a casing, a battery therein, a battery abutment secured to said casing, a spring holding said battery against said abutment, a metal head attached to the front end of said casing, a lens and a reflector secured to the front end of said head, a lamp support of insulating material mounted to slide in said abutment, a lamp carried by said support, an adjusting shaft positioned transversely of said casing, means connecting said adjusting shaft with said lamp support to move said lamp support and thereby change the character of the beam of light delivered by said hand lamp, and means for maintaining electrical connection with said lamp during adjustment thereof.
14. In a hand lamp, the combination of a casing, a battery therein, a fixed battery abutment secured to said casing and having a tubular extension, a closure for the rear end of said casing, a spring carried by said closure and holding said battery against said abutment, a metal head attached to the front end of said casing, a lens and a reflector secured to the front end of said head, a lamp support of insulating material mounted to slide in the tubular extension of said abutment, a lamp threaded into said support, an adjusting shaft positioned transversely of said casing, a nut threaded to said shaft and actuated thereby and operative to move said support axially of said hand lamp and thereby change the character of the beam of light delivered by said hand lamp, and means for maintaining electrical connection with said lamp during adjustment of said shaft.
15. In a hand lamp, the combination of a casing, a battery therein, a fixed battery abutment secured to said casing, and having

- a tubular extension, a closure for the rear end of said casing, a spring carried by said closure and holding said battery against said abutment, a flaring metal head rigidly attached to the front end of said casing, a lens holder threaded to said head, a reflector clamped between said lens holder and the end of said head, a cylindrical lamp support of insulating material mounted to slide in the tubular extension of said abutment, a lamp threaded into said support, a collar encircling said support and having a yielding finger in contact with the outer lamp terminal, a lug on said collar, a conductor yieldingly bearing on said lug, switch mechanism between said conductor and said closure spring, an adjusting shaft positioned transversely of said casing and operable from the outside thereof, an inclined slot in said lamp support, and a nut 30 threaded to said shaft and movable along said slot to move said support axially of said hand lamp and thereby change the character of the beam of light delivered by said hand lamp, and means for maintaining 35 electrical connection with said lamp during said adjustment.
16. In a hand lamp, the combination of a casing, a battery therein, a fixed battery abutment secured to said casing and having a tubular extension, a closure for the rear end of said casing, a spring carried by said 40 closure and holding said battery against said abutment, a flaring metal head at the front end of said casing, a lens holder threaded to said head, a reflector clamped between said lens holder and the end of said head, a cylindrical lamp support of insulating material mounted to slide in the tubular extension of said abutment, a lamp threaded into said support, a collar encircling said support and having a yielding finger in contact with the outer lamp terminal, a lug on said collar, a conductor yieldingly bearing on said lug, switch mechanism between said conductor and said closure spring, an adjusting shaft positioned transversely of said casing, a nut threaded to said shaft and having an inclined face, said nut fitting in an inclined slot in said lamp support and operative to move said support axially of said 45 hand lamp and thereby change the character of the beam of light delivered by said hand lamp, and a spring maintaining electrical connection between said lamp and said battery during said adjustment.
17. In testimony whereof I affix my signature
ARTHUR L. STAPLES. 50
